Primary Examiner — Robert A Delehanty(74) Attorney, Agent, or Firm — Birchwood IP(57) CLAIM

The ornamental design for a portable toilet, as shown and described.

DESCRIPTION

FIG. 1 is a front, bottom and right side perspective view of a portable toilet, showing my new design;

FIG. 2 is a rear, top and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the portable toilet that form no part of the claimed design.
